LOCK FOR GUY STRAND GUARDS

Jasper Blackburn, Webster Groves, Mo.

Application March 17, 1932, Serial No. 599,405

9 Claims. (Cl. 189—31.5)

This invention relates to locks for guy strand guards. Ordinarily, these guards are of sheet metal and are tubular or segmental in cross section, and various forms of locks are provided for mounting the guards upon the guy strands, wires or cables used to support telephone or telegraph poles, or for similar purposes.

It is the primary purpose of the present invention to provide in simple, practical and efficient form, improved means for anchoring conventional forms of guy wire guards upon the guy wires.

Another object is to provide a form of lock for mounting a guard upon a guy wire or cable, the locking element thereof having a cable-way opening out through one side or margin, whereby the device is seated upon the cable or guy strand, and including manually operable means for pressing the inserted guy strand against the innermost or closed end of the cable-way for the purpose of effectually locking the device upon the strand.

Another object is to provide in a device of the character described, a locking member having an elongated cable-way opening out through one margin thereof and manually operable means for pressing the inserted cable to its seat longitudinally through said cable-way and lockingly holding it in such position.

The said objects and purposes of the invention as referred to may be accomplished through the agency of various specific devices operating upon certain generic principles common to the several specific forms, and with the stated objects and purposes in view as aforesaid, together with such incidental advantages as may appear, attention is directed to the accompanying drawings as exemplifying several specific embodiments of my invention and wherein

Figure 1 is a frontal elevation of a latch finger form of cable lock constructed in accordance with my invention, the same being shown mounted within a form of guy wire guard, and lockingly engaging a relatively large anchor rod.

Figure 2 is a similar view showing a guy strand locked therein, the latter being shown in section.

Figure 3 is an edge view of the form of lock shown in Figures 1 and 2, as mounted within the said guard, a fragment of the latter being shown in longitudinal section.

Figure 4 is an edge view taken oppositely to the view of Figure 3, of the form of lock shown in the preceding figures, the guard being omitted.

Figure 5 is a detail of the lock finger employed

in the form of lock shown in the preceding figures.

Figure 6 is a section through another or lock-pin form of lock as mounted within a conventional form of guard, and positioned upon a guy strand, the guard and guy strand being shown in section and the lock pin being shown withdrawn.

Figure 7 is a view similar to that of Figure 6, showing the assembly turned ninety degrees from the position represented in Figure 6, as for the purpose of allowing the lock pin to fall into place.

Figure 8 is a view similar to those of Figures 6 and 7, the assembly being turned back to the position represented in Figure 6, after the lock pin has been thrown out below the guy strand through the turning movement represented in Figure 7.

Figure 9 is a fragmental sectional view similar to the views of Figures 6, 7 and 8, showing a conical and threaded form of lock pin, as a suggested modification of the lock pin represented in Figures 6, 7 and 8.

Figure 10 is a section through another or lock-screw form of lock as mounted within a conventional form of guard and positioned upon a guy strand, the guard and guy strand being shown in section and the lock screw being shown in full lines.

Figure 11 is a section on the line 11—11 of Figure 10.

As shown in Figures 1 to 5 inclusive, the form of cable or guy wire lock therein represented comprises a block A having an opening 2 extended out through one margin of the block to form a cable-way. The block A is not of uniform thickness but is reduced as shown at 3 at one side of the cable-way to form a centrally positioned web 4 disposed in parallelism with the faces of the block A. At its opposite or thicker side, the block A is bifurcated in the direction of the extended plane of the web 4, whereby are formed two spaced webs 5 at that side of the cable-way 2. These spaced webs 5 are then again pierced transversely by elongated arcuate slots 6, extended substantially the length of the webs. An arcuate latch finger 7 is loosely hinged at one end between the slotted webs 5 by means of a pin 8 passed transversely through the end, the ends of the pin itself being loosely passed into the slots 6 at either side. Keeper lugs 9 and 10 are rigidly mounted upon the two opposite faces of the web 4, one of the lugs as 10 being located further inward of the structure than the other lug 9, for a purpose

to be later explained. The arrangement is such that the free end 11 of the latch finger 7 may be readily positioned at either side of the web 4 by merely sliding the pin 8 inwardly along the slots 6 to the position shown in dotted lines in Figure 2. In such position, the end 11 will be drawn in so as to clear the web 4 and may then be moved or swung to either side of the said web. The pin 8 may then be slid outwardly along the slots 6 and the end 11 of the latch finger 7 may be located upon the keeper lug at that side of the web 4. This form of lock may be used in connection with any conventional form of guard 12 and may be anchored to the guard in any desired manner, as 15 by cutting and turning outwardly the flanged margins of the guards at each side of the block A, as shown at 13. A guard so prepared with a number of the blocks A mounted therein in spaced relation in conventional manner, may be set over a guy strand 14 or over a relatively larger anchor rod 14a, either of which may be passed into the cable-way 2, for this purpose the finger 7 being withdrawn from its position across the cable-way. With the guy strand or anchor rod properly located, the finger 7 of each lock is moved outwardly along the slots 6 and the free end 11 is swung across the cable-way and placed in engagement with one of the keepers 9 or 10 upon the web 4, that keeper being selected which 20 will cause the finger to bear with the requisite degree of pressure upon the strand 14 or rod 14a in order to firmly hold the two elements in locked relation. Upon the larger anchor rod 14a, the more outwardly located lug 9 would probably be employed for latching the end 11 of the finger 7, while for the guy strand 14 of less diameter, the lug 10 would be utilized. It will thus be seen that the variously spaced keeper lugs 9 and 10 in combination with the latch finger 7, afford 25 handy means for the accommodation of wires or rods of various diameters. A cable seat 15 may be formed upon the finger 7 as means for preventing the edge of the finger cutting into the cable or strand 14. The conventional socket 16 may be formed in the block in alignment with the cable-way 2, and a threaded bore 17 extended out through the same to receive the usual set screw 18 for cooperating with the lock finger 7, there being a registering aperture 19 cut through the 30 guard at this point.

In the use of the lock described, it will be noted that the pressure of the finger 7 upon the guy strand is exerted in a direction substantially longitudinally inward of the cable-way 2, and so as to press the strand towards and against the closed end 36 of the cable-way, thereby locking it firmly in place.

In the assemblies represented in Figures 6 to 8 inclusive, the block B is of substantially uniform thickness and is provided with a cable-way 2b similar to that of the block A, and whereby the block B is partially divided, forming two branches or lobes 20. A pin or bolt socket 21 is formed in one of the lobes 20 perpendicularly to the cable-way 2b and having a mouth or opening 22 thereinto at a point somewhat out from the inner closed end of the cable-way. At its outer end this socket opens out through the margin of the block, as shown at 23. Immediately back of its inner mouth 22, the socket is enlarged or offset laterally, as shown at 24, the same being so located as to stand positioned at the proposed lower side of the block as in actual use. In the opposite lobe 20 immediately across from and in axial alignment with the socket 21, is formed a keeper socket

25. A lock pin or bolt 26 is loosely mounted within the socket 21, the inner end 27 of the pin being adapted to pass through the inner opening 22 of the socket and across into the keeper socket 25, the outer end of the pin being formed with a laterally expanded head 28 adapted to fall into the offset recess 24 when the pin is moved fully inward to its strand locking position, as will be later described. A tool socket 29 is pierced longitudinally into the head of the pin 26 for facilitating the placing of the pin in manner to be described. When mounted within a guard 12b, an aperture 30 is cut through the guard in alignment with the socket 21, the said aperture being less in diameter than the head of the pin 26, so that the latter may not fall out through said aperture. The conventional structural features of set screw and socket, as indicated at 16, 17, 18 and 19 in Figures 1 and 2 of the first described form of lock, may be duplicated of course in the form shown in Figures 6, 7 and 8, as indicated at 16b, 17b, 18b, and 19b.

In the use of this lock, after it is seated over the guy wire 14b as shown in Figure 6, the pin 26 being withdrawn, the assembly is turned ninety degrees in an anti-clockwise direction to the position shown in Figure 7, whereupon the pin 26 will fall partly through the opening 22, the end 27 will drop into the keeper socket 25, and the head 28 into the recess 24. The assembly may then be returned to its original position without danger of the pin 26 removing or becoming withdrawn from its locking position relative to the strand 14b, because the head 28 resting in the recess 24, prevents such action. If necessary, in order to facilitate placing the end 27 of the pin within the socket 25, a pointed instrument such as a wire (not shown) may be inserted within the tool socket 29, the said wire serving as a handle extended out through the aperture 30 provided in the guard.

A modification of the last described form is shown in Figure 9. Here the keeper socket is a tapped bore 25c. The pin 26c is conical as shown and is provided with a kerf 31 for the accommodation of a screw driver (not shown) inserted through the aperture 30c of the guard 12c. With this arrangement, turning up the cone shaped pin 26c operates to force the cable 14c inwards against the closed end of the cable-way 2c, and in this operation, the resultant action of the conical pin 26c upon the strand 14c is substantially similar to the action of the latch 7 upon the strand 14, as described and shown with reference to the structures of Figures 1 to 5.

In the assembly represented in Figures 10 and 11, the block D is of uniform thickness and is formed with the cable-way 2d similar to the previously described structures. In this form, however, the inner end of the cable-way is slightly constricted or narrowed, as shown at 2d', and this narrowed portion is then tapped and threaded upon its margins as shown at 32. A threaded plug 33 having a kerf 34 in its outer end, is provided for this threaded cable-way, and a rotatable bearing 35 may also be provided for the inner end of the plug if desired. This form of lock is mounted within the guard 12d in manner similar to the others above described. In the use of this form, the screw plug 33 is removed, and the guy strand 14d being properly seated within the cable-way 2d, at the inner end thereof as shown in Figure 10, the plug is then screwed into place in its threaded seat 32, thus pressing the strand 14d

forcibly against the closed end 36d of the cable-way 2d and locking it securely in place.

It is thought from the foregoing description that the use and operation of the several forms of locks will be fully understood. Any of the described forms may, of course, be anchored within the guards in the same manner as that pointed out in reference to the first described form represented in Figures 1 and 2, and as indicated by the analogous numbering of the corresponding parts and structural features, where such exist in the several forms. And, of course, any other means not shown may be employed for mounting the locks in place within their guards. Moreover, while certain forms and shapes of guards are here shown in connection with the description of my invention, and the locks themselves are represented as conforming to such shapes, it is understood that by proper modification and adaptation, either of the several forms of my invention might or could be used upon guards of other shapes or forms, as might be desired, and while I have herein described and shown certain assemblies of elements and structural features as more prominently characterizing my invention, it is understood that I may vary and modify the said elements and structural features, in details and matters not departing from the spirit of my invention, as defined in the appended claims.

30 I claim:

1. In a device of the kind described, a member having a cable-way opening out through one margin, the member comprising a single centrally positioned web at one side of the cable-way and two spaced webs at the opposite side of the cable-way, the said spaced webs being pierced transversely by elongated aligned slots extended in substantial parallelism with the cable-way, keeper lugs upon the opposite faces of the said single web and arranged in a stepped relation, and a latch finger having a pin passed transversely through one end, the ends of the pins being placed in slidable engagement with the said slots of the spaced webs, the free end of the latch finger being adaptable for positioning in engagement with either of the said keeper lugs at either side of the said central web of the structure.

2. A device of the kind described, comprising a block having an opening extended out thru one margin to form a cable-way, the block including at one side of the cable-way two spaced webs and at the opposite side of the cable-way a centrally positioned web, all said webs being arranged in substantially parallel planes, and means cooperating with the formation and arrangement of the said webs for releasably locking a guy strand within the said cable-way.

3. In a device of the kind described, a unitary member formed with a plurality of webs arranged at opposite sides thereof in substantially parallel planes and in an edgewise spaced relation to provide a cable-way therein between, and means cooperating with the formation and arrangement of the webs for releasably locking a guy strand within the cable-way thereof.

4. In a device of the kind described, a member including webbed portions arranged partly at one side and partly at the other in substantially

parallel planes and in an edgewise spaced relation to provide a cable-way therein between, and a latch member loosely connected at one end between the webs at one side and adapted at the opposite end to close over the cable-way to the webs at the opposite side, and means upon the webs at said opposite side for adjustably and releasably locking the latch member to its closed position.

5. In a device of the kind described, a member having a plurality of webs arranged oppositely in spaced relation to provide a cable-way therein between opening out thru one margin, the webs at one side of the cable-way being slotted in alignment, a latch finger slidably mounted at one end within said slots, the free end of the latch finger being adapted to close athwart the cable-way to the opposite webs, and means upon the latter webs for releasably locking the free end of the latch finger when turned athwart the cable-way.

6. The combination with a guy-strand and a guard adapted to lie along the strand, of a lock for connecting the two, the same comprising a member having a cable-way opening out thru one margin and including at one side of the cable-way slotted webs, a latch finger loosely mounted at one end within said slots, means at the opposite side of the cable-way for releasably holding the free end of the latch finger, and means for securing the lock to the guard.

7. In combination with a guy-strand, a lock for mounting a guard upon the strand, the same comprising a member having a cable-way to receive the strand, a latch finger pivotally and slidably connected at one end to one lateral margin of the cable-way and adapted at its free end to close athwart the cable-way to the opposite margin thereof, and means at said opposite margin for adjustably and releasably engaging the free end of the latch finger.

8. A lock for mounting a guard upon a guy strand, the same comprising a member having a cable-way opening out thru one margin and thereby adapted to receive the strand, the member being formed at one margin of the cable way 45 to pivotally and slidably engage an end of a latch finger, a latch finger thus pivotally and slidably connected at one end to the prepared margin of the cable way and adapted at its free end to close across the cable-way to the opposite margin 50 thereof, and means on said opposite margin for releasably engaging the free end of the latch finger.

9. A lock for mounting a guard upon a guy strand, the same comprising a member having a cable-way closed at its inner end and opening at its other end out thru one margin thereof for receiving the strand, a latch finger, one margin of the cable-way and one end of the latch being cooperatively formed for pivotally and slidably connecting the end of the latch finger to and upon the said margin of the cable-way, with free end of the latch finger being movable across the cable-way to the opposite margin thereof, and means on said opposite margin for releasably engaging the free end of the latch finger.

JASPER BLACKBURN.
